UNITED STATES PATENT OFFICE.

JOHN WILLIAM HARKOM, OF MELBOURNE, QUEBEC, CANADA.

VALVE.

1,112,135.

Specification of Letters Patent. Patented Sept. 29, 1914.

Application filed May 9, 1913. Serial No. 766,545.

To all whom it may concern:

Be it known that I, JOHN WILLIAM HARKOM, of the village of Melbourne, in the county of Richmond, in the Province of Quebec, Canada, have invented certain new and useful Improvements in Valves, of which the following is the specification.

My invention relates to improvements in valves and the object of the invention is to provide a valve having a passage for the fluid entirely unobstructed either by the valve head or valve operating mechanism, in which the valve head may be locked tight on its seat to prevent the inlet of steam into the valve casing during the renewal of the packing, in which the valve seat may be easily removed, and in which the valve seat may be easily gotten at for the purpose of regrinding and it consists essentially of a valve casing having an outlet port and an inlet port provided with a valve seat, a valve therefor and resilient means designed to raise the valve off its seat into a position out of the path of the travel of the fluid passing through the casing from inlet to the outlet port and means also out of the path of the fluid for forcing the valve closed, a locking device designed to hold the valve head tight on its seat and a removable valve seat as hereinafter more particularly explained by the following specification.

Figure 1, is a perspective view of my valve designed for low pressure partially broken away and in section to exhibit the interior construction thereof. Fig. 2, is an enlarged vertical section through Fig. 1. Fig. 3, is an enlarged perspective view of the operating spring. Fig. 4, is a sectional view showing a modification of my valve adapted for high pressure. Fig. 5, is a further modification of my valve as adapted for high or low pressures.

In the drawings like letters of reference indicate corresponding parts in each figure. In Figs. 1 and 2 A is a valve casing provided with an inlet port A¹, an outlet port A² and an internally threaded opening A³ formed in the wall of the casing opposite the inlet port A¹ and in alignment therewith. A⁴ is an opening in the wall of the casing opposite the outlet port A². A⁵ is a flange extending outwardly from the casing A around the opening A⁴, such flange being provided with a recess A⁶. A⁷ is a metallic diaphragm secured around its edge to the face of the flange A⁵ and provided with a

normally upwardly arched central portion A⁸. A⁹ is a cap secured to the flange A⁵ by tap screws A¹⁰. The inner face of the cap is provided with an arched recess A¹¹ into which the arched portion A⁸ of the diaphragm A⁷ normally fits. A¹² is a boss extending outwardly from the cap A⁹ and provided with an internally threaded orifice A¹³. B is a threaded operating stem of the valve provided with a suitable handle B¹. The stem B is threaded into the orifice A¹³ so that the inner end bears against the arched portion A⁸ of the diaphragm A⁷. A¹⁴ is a valve seat formed around the inlet orifice A¹. C is a valve fitting the valve seat A¹⁴. C¹ is a pin extending through the valve casing in proximity to the diaphragm A⁷. C² is a lever arm pivoted at one end on the pin C¹ and connected at the opposite end by a pin C³ extending through lugs C⁴ formed integral with the valve C. C⁵ is a lever arm extending from the inner end of the lever arm C² against the arch portion A⁸ of the diaphragm A⁷. D is a threaded plug fitting the internally threaded orifice A⁸. E is a locking screw extending through the bushing nut E¹ threaded into the orifice E² of the valve casing. The screw E is normally in the position shown in full lines.

F is an operating spring comprising a U-shaped portion F¹ (see Fig. 3), the arms of which are bent backwardly upon themselves in U-shape form F², that portion of the spring extending between the U-shape portion F² and the U-shaped portion F¹ is bent slightly into an obtuse angle at F³. The spring F is located between the casing A and the lever arm C² so as to bear against the under face of the lever to hold the lever arm C⁵ against the diaphragm A⁷.

When it is desired to open the valve I unscrew the operating stem B allowing the resilient washer A⁷ to resume its normal arch-shaped form. The spring F then carries the lever arm C² upwardly and the valve C away from its seat A¹⁴ in an arc-shaped direction. When closing the valve the stem B is threaded through the orifice A¹³ against the arch shaped diaphragm A⁷ forcing the cam portion C⁵ inwardly and the lever arm C² against the tension of the spring F and carrying the valve C on to its seat. When it is desired to permanently lock the valve in this position so as to prevent the fluid flowing into the valve casing the screw E is threaded through the bushing E¹ against the

lever arm C². The cap A⁶ may then be removed and the diaphragm A⁷ may be replaced by a new one if required without allowing the escape of steam or other fluid.

- 5 In Fig. 4, I have shown the same principle of construction of valve as applied to high pressure. I will now describe this form in detail. G is the valve casing provided with an inlet port G¹ and an outlet port G² and an orifice G³ over which extends the covering cap G⁴ provided with an internally threaded boss G⁵. Between the flanges of the cap G⁴ and the casing a diaphragm G⁶ is inserted provided with an arch-shaped portion G⁷. H is a stem threaded into the orifice of the boss G⁵ against the arch-shaped portion G⁷ of the diaphragm G⁶. H¹ is a removable seat which is threaded into the threaded orifice 10 G¹ forming the inlet port. I is a valve head. I¹ is a pin extending through the valve casing to one side of the inlet port G¹. I² is a lever swung upon the pin I¹ and connected to the valve I by a pin I³ extending through 15 the lugs I⁴ carried by the valve I. I⁵ is a slot formed in the lever I². J is a supplemental lever pivoted upon a pin J¹ extending into the valve casing. The lever J is provided with a notched portion J² and a pin J³ extending into the slot I⁵. K is a lug which constitutes one arm of the lever I². L is a locking screw extending through a bushing L¹ and provided with a head L² provided with a soft washer L³ designed 20 when the locking screw is withdrawn to bear against the wall of the casing and form a fluid tight joint with the casing G opposite the lug K. M is a spring bent in substantially V-shaped form and having one arm resting against the side of the casing and the other arm entering the notch J² of the supplemental lever J.

By unscrewing the stem H the arch portion of the diaphragm assumes the position shown in dotted lines and the spring M then acts to swing the lever J into the dotted position, the pin J³ moving along the slot I⁵ thereby gradually swinging the arm of the lever I² which carries the valve upwardly carrying the valve I to the dotted position shown, out of the path of the liquid passing between the inlet port G¹ and the outlet port G².

When it is desired to lock the valve closed, for the purpose of repairing the packing the screw L is threaded against the lug K securely holding the valve I in its closed position.

Where a straight way valve is required, that is to say, with the inlet port directly in alinement with the outlet port I have provided the construction shown in Fig. 5. In this form the casing N is provided with an inlet port N¹ and an outlet port N² in alinement therewith. In the face of the valve

casing parallel with the path of the fluid is formed an opening N³ provided with a covering cap N⁴ in which the operating valve stem N⁵ is threaded. N⁶ is the valve head provided with lugs N⁷. N⁸ is a lever pivoted to one side of the inlet port N¹ on a pin N⁹. N¹⁰ is a slot formed in the lever N⁸. The lever N⁸ extends upwardly in an inclined direction over the valve head N⁶ and is provided with a lateral extension N¹¹ through which the lugs N⁷ extends a pin N¹². O is a supplemental lever pivoted on a pin O¹ in proximity to the diaphragm O². The supplemental lever O is provided with a cam extension O³ bearing against the diaphragm O² and forming a notch O⁴ into which an operating spring P extends. The supplemental lever O extends substantially at right angles to the slot N¹⁰ in the lever N⁸ and is provided with a pin O⁷ extending into the slot N¹⁰. By this mechanism when the operating valve stem N⁵ is unscrewed and the diaphragm O² assumes its normal position shown by dotted lines the spring P forces the lever O into the position shown by dotted lines carrying the lever N⁸ and valve head N⁶ outwardly in an arched direction into the dotted position out of alinement with the inlet and outlet orifices N¹ and N². Q is a locking screw which is threaded inwardly against the lever N⁸ thereby locking the valve head N⁶ securely on its seat when required.

From this description it will be seen that I have devised very simple constructions 100 of valves adapted both for high and low pressures to either angle or straight way valves through which there is an unobstructed flow of fluid when the valve is opened, in which the valve may be easily 105 locked in position to prevent the flow of steam through the valve when it is desired to remove the packing of the valve and which can be made absolutely fluid tight, and in which the seat of the valve may be 110 easily gotten at for the purpose of re-grinding.

What I claim as my invention is—

1. In a valve, the combination with the valve casing having an outlet port and an 115 inlet port provided with a valve seat, of a valve co-acting with the valve seat, an operating valve mechanism extending through the casing out of alinement with the inlet port, and a lever co-acting with the operating mechanism to hold the valve on its seat and a spring to move the valve out of the path of the fluid between the inlet and outlet ports when the pressure of the operating mechanism is removed from said lever.

2. In a valve, the combination with the valve casing having an outlet port and an inlet port provided with a valve seat, of a valve co-acting with the valve seat, a lever pivoted at one end to the valve and at the 130

opposite end to the casing at one side of the inlet port and resilient means for throwing the end of the lever upwardly in an arc-shaped direction to carry the valve off its seat and out of the path of the fluid flowing between the inlet and outlet ports, and means for forcing the valve closed against such resilient means, as and for the purpose specified.

- 10 3. In a valve, the combination with the valve casing having an outlet port and an inlet port provided with a valve seat, of a valve co-acting with the valve seat, a lever pivoted to the casing at one end at one side 15 of the valve seat and to the valve at the opposite end and an operating mechanism extending through the casing and co-acting with the lever to lower the valve in an arc-shaped direction on to its seat, and a resilient means for raising the valve out of the path of the fluid flowing between the inlet and outlet ports when the valve operating mechanism is withdrawn, as and for the purpose specified.
- 20 4. In a valve, the combination with the valve casing having an outlet port and an inlet port having a valve seat, of a valve co-acting with the valve seat, an orifice in the valve casing out of the path of the fluid 25 travel, a resilient imperforate diaphragm extending over the orifice, a covering cap extending over the diaphragm and secured to the casing, a valve operating mechanism

bearing against the diaphragm, and a lever having a tail piece bearing against the dia- 35 phragm and pivotally supporting the valve at its opposite end, and resilient means for raising the valve off its seat, as and for the purpose specified.

5. In a valve, the combination with the valve casing having an inlet and an outlet port, of a valve co-acting with the inlet port, resilient means for raising the valve off its seat in an arc-shaped direction, mechanism for operating the valve, and 45 means independent of the valve operating mechanism for locking the valve tight on its seat, as and for the purpose specified.

6. In a valve, the combination with the valve casing having an inlet and an outlet 50 port and provided with a valve seat, a lever pivoted at one side of the valve seat and pivotally connected with the valve, a set screw threaded in the casing and designed to be screwed against the lever to lock the 55 valve in its closed position, and a valve operating mechanism co-acting with the lever to close the valve, and resilient means for raising the lever which carries the valve on its pivot when the valve operating mechanism is withdrawn, as and for the purpose 60 specified.
